(57) **CLAIM**

The ornamental design for a heel pad for a shoe, as shown and described.

DESCRIPTION

FIG. 1 is a perspective view of the heel pad for a shoe of the present invention;

FIG. 2 is a front view of the heel pad for a shoe in a closed position;

FIG. 3 is a back view of the heel pad for a shoe in the closed position;

FIG. 4 is a left side view of the heel pad for a shoe in the closed position, the right side being a mirror image thereof; FIG. 5 is a top view of the heel pad for a shoe in the closed position;

FIG. 6 is a bottom view of the heel pad for a shoe in the closed position;

FIG. 7 is a front view of the heel pad for a shoe in an open, flattened position;

FIG. 8 is a back view of the heel pad for a shoe in an open, flattened position;

FIG. 9 is a top view of the heel pad for a shoe in an open, flattened position; and,

FIG. 10 is a perspective view of the heel pad for a shoe, shown in use.

The broken lines in the drawings illustrating a shoe are environmental structure and form no part of the claimed design. All other broken lines illustrate portions of the heel pad for a shoe that form no part of the claimed design.

1 Claim, 9 Drawing Sheets
